UNITED STATES PATENT OFFICE.

GEORGE P. THOMAS, OF GLENSHAW, PENNSYLVANIA.

METAL-PUNCHING MACHINE.

Application filed May 11, 1923. Serial No. 638,270.

To all whom it may concern:

Be it known that I, GEORGE P. THOMAS, a citizen of the United States, and a resident of Glenshaw, in the county of Allegheny and State of Pennsylvania, have invented a new and useful Improvement in Metal-Punching Machines, of which the following is a specification.

The invention relates to machinery for 10 punching rivet and bolt holes in metal blanks, especially in structural material such as steel plates, angles, beams and other sections, and has particularly to do with machinery of this type which includes a punch 15 and spacing carriage having inter-dependent electrically-operated elements, and also has to do with spacing carriages which are driven by electric motors mounted on them but which may not have any electrically- 20 operated elements controlled by or which control the punches with which the carriages are associated.

Machines of this type are shown in several 25 of my prior patents. For example, my Patent No. 835,123 shows a machine including a spacing carriage driven by an electric motor, and a punch having gags operated by electro-magnets, the circuits through which magnets are controlled by mechanism 30 on the carriage. Similar machines having in some instances the same and in others different inter-dependent electrically-operated elements are shown in my Patents Nos. 886, 551, 1,068,465, 1,141,221 and 1,175,198.

In all of these machines the practice has been as is explained and illustrated in said 35 Patents Nos. 835,123 and 886,551, to arrange the required number of electric conductors along the side of the tables on which the carriages travel, and to provide the carriages with arms or trolleys which contact with the conductors as the carriages move upon the tables. This has necessitated the presence of long lines of more or less exposed 40 uninsulated conductors, some of which, particularly the motor circuit conductors, carry heavy currents, and are accordingly dangerous.

An object of this invention is to provide 45 machines of the type explained with mechanism to the end that the presence of exposed uninsulated lines of conductors may be eliminated.

A further and more specific object is to 50 provide a spacing carriage for a metal punching machine with a drum or equiva-

lent device for receiving and properly paying out insulated conductors forming part of a circuit for supplying current to an electric carriage-driving motor mounted on 60 the carriage, and also forming parts of circuits for supplying current to such inter-dependent electrically-operated elements as may be borne by the carriage and the punch with which it is associated. 65

The invention is illustrated in the accompanying drawings of which Fig. 1 is a somewhat diagrammatic side elevation of a punch, work table, and spacing carriage movable upon the table; Fig. 2 a plan view 70 of the machine shown in Fig. 1; Fig. 3 an enlarged plan view of the drum at the right end of the spacing carriage shown in Fig. 1; and Fig. 4 an end elevation of the drum shown in Fig. 3. 75

In the practice of the invention insulated conductors are used for inter-connecting the inter-dependent electrically-operated elements of a punch and spacing carriage, and also for the spacing carriage motor circuit. 80 The spacing carriage is provided with means for taking up and paying out the conductors as the carriage moves to and fro, so constructed and arranged as to prevent the conductors from interfering with the 85 operation of the machine, and also to avoid injuring the conductors or their insulation. The preferred means for this purpose is a drum mounted upon the carriage and rotated in such manner that, depending upon 90 which way the carriage moves, the conductors are properly reeled upon or paid from the drum. While various means may be provided for rotating the drum, it is preferred to rotate it by connections extending from the driving mechanism of the carriage. The necessary conductors may be, and preferably are, embodied in a single cable which extends from the carriage to the end of the work table remote from the punch, and the 95 rotation of the drum is such that as the carriage moves from the punch the cable is wound upon the drum, and as it moves toward the punch the cable is paid out. It 100 will be understood, however, that this arrangement may be reversed. 105

The invention is illustrated in its applicability to a spacing carriage of the type disclosed in my Patents Nos. 1,068,465 and 1,245,530, although it is manifestly applicable to other types of punching machinery, including those disclosed in the other 110

of my patents mentioned above. Having reference first to Figs. 1 and 2, a spacing table 1 and a feed table 2 are shown extending from opposite sides of a punch 3. Upon the spacing table there is a spacing carriage 4 adapted to move a blank 5 from the feed table through the punch and to stop its movement at the required intervals for punching it.

10 As to the electric elements borne by the spacing carriage and punch, the carriage is moved by an electric motor 6, which, through suitable connections indicated in the drawings, rotates a shaft 7 provided
15 with pinions 8 which engage racks 9 mounted on the spacing table, and is stopped by the tripping or releasing of pawls 10 to permit them to engage a detent bar 11 also mounted on the table. During the opera-
20 tion of the machine motor 6 is continuously driven. The driving connections between it and shaft 7 include a magnetic clutch 12 a circuit through which is interrupted to break the driving connections by means of
25 a contactor 13 which is caused to move from a contactor 14 when pawls 10 are released. Punch 3 is provided with a magnetically operated clutch 15, the circuit through which is adapted to be closed
30 through contactors 16 and 17 borne by the spacing carriage. To release pawls 10 at the completion of a punching operation, the carriage is provided with an electro-magnet or solenoid 18 the circuit through which is adapted to be closed by means of contactors 19 and 20 on the punch when the reciprocating head of the punch rises. The particular manner in which these several electrically-operated inter-dependent ele-
35 ments are constructed and operate, and the detailed construction and operation of the punch and spacing carriage are fully described and shown in my said Patents Nos. 1,068,465, 1,141,221 and 1,245,530, and accordingly need not be further explained
40 herein.

At the end of the carriage remote from the punch there is rotatably mounted a drum 25 on which there is wound a multiple electric conductor cable 26 containing conductors for the motor circuit and for the inter-dependent electrically-operated elements just explained. As previously stated, the cable preferably extends from the carriage to the end of the spacing table remote from the punch. At the end of the table there may be a roller 27 over which the cable passes, and to hold the cable fairly taut between the roller and the spacing carriage, a weight 28 may be attached to the cable. The drum may be positively rotated to reel the cable upon and pay it out from the drum by connections extending from the driving mechanism. As shown in the drawings, these driving connections may include a

sprocket wheel 29 mounted on shaft 7, a sprocket wheel 30 mounted on the axle 31 of the drum, and a sprocket chain 32 extending over these sprocket wheels.

One end of the cable 26 is attached to drum 25, and means are provided, preferably in the form of contact rings and brushes for connecting the conductors of the cable to conductors mounted on the table and extending to the motor and other electrical elements. Preferably, the contact rings are mounted upon axle 31 of the drum and the brushes supported by the carriage. This is illustrated in Figs. 3 and 4 which show the drum axle as being provided with a series of suitably insulated contact rings 33 to which the conductors of cable 26 are electrically connected. For the sake of simplicity the details for extending the cable conductors to the contact rings are omitted, the conductors being diagrammatically shown in Fig. 3 as extending along axle 31. In contact with each ring there is a brush 34 mounted in an arm 35 and supported by a bracket 36 attached to the frame of the carriage. Each brush is held yieldingly in contact with a ring 33 by means of a spring-pressed arm 37 which acts upon the outer end of the brush.

In the operation of the machine the spacing carriage 4 is intermittently moved to advance a blank 5, and the punch is intermittently operated in coordination with the movements of the carriage to punch the blank, all in the manner fully disclosed in my prior patents mentioned above. The conductors for the motor circuit and for the inter-dependent electric elements are all carried by cable 26. Drum 25 to which an end of the cable is attached and on which it is wound, is rotated in coordination with the movements of the carriage so that the length of cable wound upon or paid out from the drum is the same as the movement of the carriage. Thus the requisite electric circuits and connections are established for the carriage motor circuit and for the inter-dependent electric elements of the punch and carriage without the use of exposed uninsulated conductors at the side of the spacing carriage. 115

According to the provisions of the patent statutes I have described the principle and operation of my invention together with the construction which I now consider to be the best embodiment thereof. However, I desire to have it understood that, within the scope of the appended claims, the invention may be practiced with other forms of construction than that particularly shown and described. 120 125

I claim:

1. In a metal punching machine, the combination with a punch, a spacing table, a work carriage movable upon the table, and 130

inter-dependent electrically-operated elements borne respectively by said punch and carriage; of a drum rotatably mounted on said carriage, insulated electric conductors 5 on said drum and connecting said electrically-operated elements borne by the punch with those borne by the carriage, and means for rotating the drum to reel the conductors upon and to pay them out from it as the 10 carriage moves toward and from the punch.

2. In a metal punching machine, the combination with a punch, a spacing table, a work carriage movable upon the table, means for driving the carriage, and inter-dependent electrically-operated elements 15 borne respectively by said punch and carriage; of a drum rotatably mounted on said carriage, insulated electric conductors wound upon said drum and connecting said 20 electrically-operated elements borne by the punch with those borne by the carriage, and means coordinated with the carriage driving means for rotating the drum.

3. In a metal punching machine, the combination with a punch, a work-supporting table, a spacing carriage movable upon the table, an electric motor mounted on the carriage for driving it, and inter-dependent electrically-operated elements borne 25 respectively by said punch and carriage, of a drum rotatably mounted on said carriage, insulated conductors wound upon said drum and connecting said electrically-operated elements borne by the punch with those borne by the carriage, and connections extending from 30 said motor to said drum for rotating the drum.

4. In a metal punching machine, the combination with a punch, a spacing table, a work carriage movable upon the table, and inter-dependent electrically-operated elements 40 borne respectively by said punch and carriage; of a drum rotatably mounted on said carriage and provided with contactor rings, contact brushes mounted on said carriage, electric conductors connected to said rings and wound upon the drum and extending from the drum to said punch electrically-operated elements, and means for 45 rotating the drum to reel the conductors upon and pay them out from it as the carriage moves to and from the punch.

5. In a spacing carriage for a metal punching machine, the combination with driving mechanism and an electric motor 55 mounted on the carriage for operating said mechanism; of a drum rotatably mounted on the carriage, insulated electric conductors leading to said motor and wound upon said drum, and means for rotating said 60 drum to reel the conductors upon and pay them out from said drum as the carriage is moved.

6. In a spacing carriage for a metal punching machine, the combination with 65 driving mechanism, and an electric motor mounted on the carriage for operating the driving mechanism; of insulated electric conductors forming part of a circuit for said motor, and means borne by the carriage 70 for taking up and paying out said conductors as the carriage moves to and fro.

7. In a metal punching machine, the combination with a punch, a spacing table, a spacing carriage movable upon the table, and an electric motor mounted on the carriage for driving it; of insulated electric conductors forming part of a circuit for 75 said motor extending from the carriage to the end of the spacing table remote from the punch, and means borne by the carriage for taking up and paying out said conductors as the carriage moves to and from the punch.

8. In a metal punching machine, the combination with a punch, a spacing table, a work carriage movable upon the table, driving mechanism including an electric motor for driving the carriage; of a drum rotatably mounted upon the carriage and provided 85 with contactor rings, brushes mounted upon the carriage and contacting with said rings, insulated electric conductors for said motor wound upon said drum and extending longitudinally of said table, and connections between said carriage-driving mechanism and said drum for rotating the drum to reel the conductors upon and pay them out from it as the carriage moves to and from the punch.

In testimony whereof, I sign my name.

GEORGE P. THOMAS.

Witness:

EDWIN O. JOHNS.
